COOLING TOWER CONSTRUCTION

Edward W. Simons, San Francisco, Calif., assignor
to Redwood Manufacturing Co., Pittsburg,
Calif., a corporation of Nevada

Application April 14, 1939, Serial No. 267,809

4 Claims. (Cl. 261—111)

This invention relates to cooling towers, and has for its objects improved construction in such towers providing greater cooling efficiency and greater economy of water by substantial elimination of the loss in water due to objectionable drifting thereof out of the tower. Another object is the provision of a tower in which the walls comprise rows of vertically elongated spaced elements arranged to permit passage of air through the walls and to promote high cooling efficiency under both normal and abnormal wind conditions, and a still further object is a construction in a tower in which the shape of said elements contributes materially to effectively controlling the flow of air through the tower in a manner to insure best results for any and all conditions that occur due to normal or abnormal wind velocities or sudden changes in such velocities.

Other objects and advantages will be apparent from the description and drawings annexed here-to.

In the drawings,

Fig. 1 is a side view, partly in elevation and partly in section, with a portion between the top and bottom ends thereof removed to accommodate the view to the sheet.

Fig. 2 is an enlarged sectional view through two opposed sides of a cooling tower, as seen along line 2—2 of Fig. 1, with dash lines and arrows indicating the path of air across the tower.

Fig. 3 is a fragmentary sectional view taken along line 3—3 of Fig. 2.

Fig. 4 is a greatly enlarged sectional view, showing the louvers, slats, strips or the like of one of said walls, and which figure is also intended to show the preferred cross-sectional contour of said louvers, etc.

Figure 5 is a cross-sectional view of a modified form of one of the louvers, and Fig. 6 shows slightly different louvers, in a wall.

One of the most important features of this invention resides in the structure of the walls of the cooling tower. Conventional construction in cooling towers includes sides in the form of horizontally extending louvers, or solid panels, that are inclined at an angle of 45° relative to horizontal. In this invention, the walls or panels of the walls, are made up of several horizontal rows of horizontally spaced vertically extending strips or slats, or the like, one or more of which rows of elements may be termed "louvers" in this description, but which are not to be confused with the conventional horizontally extending, angularly disposed louvers as found in the various arts, including the art of cooling towers.

In detail, Fig. 1 represents a four-sided cooling tower having four corner posts, framework 2, horizontal supports 3, for supporting conventional mats, distributing decks, screens or the like 4 thereon, and walls that are generally designated 5.

The panels of louvers that form the sides of the tower are each made up of several parallel rows of horizontally spaced, parallel, vertically extending elements, all of which will generally be termed louvers. These panels are preferably disposed one above the other on each side of the tower, the number used depending upon the desired height of the tower, and also the panels may be several in number at each level on each side of the tower, depending upon the desired height of the tower, and also the panels may be several in number at each level on each side of the tower, depending upon the desired width of the tower, the corner posts being farther apart as the width is increased. It is, of course, obvious that each side of the tower may be of unitary construction, or a single panel, if so desired.

In describing the louvers in detail, and other elements associated therewith, the terms "inner," "inwardly," "outer" and "outwardly" are used with reference to the center or inside of the tower.

Referring to Fig. 2, it is seen that the inner side of each wall of the tower comprises a horizontal row of vertically extending, horizontally spaced elements 6, which will hereafter be termed "blades," or "deflector blades" to distinguish from other elements of the walls.

The blades 6 comprise strips that are relatively wide, and which strips are equally spaced apart, and are disposed in the direction of their greatest width, in parallel planes that extend normal to the plane of the panel or wall of which the strips are a part. The opposite sides of each blade extend generally divergently from its inner edge so that the thickness of the blade adjacent said inner edge is appreciably less than the thickness of the blade adjacent its opposite edge, and both the inner and outer edges are rounded, all as best seen in Fig. 4. With this construction, the blades offer substantially a minimum resistance to air currents initially engaging the outer edges thereof, while insuring substantially full engagement of such air with the opposite sides of the blades irrespective of the directional movement of the air between the outer and inner edges. Also, the divergently extending sides provide surfaces that are more efficiently disposed for catching moisture, in the form of drops or vapor, that tend to splash or drift outwardly from within the tower.

The spacing between the adjacent blades of the pairs in each row may vary, according to the installation, but it has been found satisfactory to use the spacing shown in Fig. 4, which is about two inches for blades that are about three and one-half inches wide by about one-half inch thick at the thickest part, with a taper of the sides from about one-half inch at the outer edge to about one-eighth inch at the inner edge.

The blades 6 of each wall are supported between horizontally extending battens 7, 8, the battens 7 extending across the inner edges of the blades and the battens 8 extending across the outer edges of the blades. Any number of battens may be used, but it has been found that a pair of battens 7 and a pair of battens 8, is generally sufficient for blades of about four foot lengths, in which a pair 7, 8 are adjacent the upper ends of the blades and a pair 7, 8 are adjacent the lower ends.

The battens 7, 8 and blades 6 are preferably formed with interlocking recesses or notches, as indicated in Fig. 3 at points where the battens cross the blades so as to facilitate the assembly of the blades and accurate spacing thereof as well as for insuring a rigid structure with the blades held together in the panel as a unit.

The horizontal width of battens 7 and the interlocking recesses in battens 7 and the blades, are preferably such as to position the inner edges of the blades substantially flush with the inner sides of the battens 7 when the bases of the interlocking recesses in the battens and blades are in engagement. The horizontal width of battens 8 is appreciably greater than the corresponding width of battens 7, although the interlocking recesses are of the same depth, therefore, it will be seen that the outer edges of blades 6 are spaced inwardly from the outer edges of battens 8, the purpose of which will become apparent later on.

In order to secure the battens 7, 8 in position with the interlocking recesses of the battens and blades in interlocked relation, several vertically extending strips 9 are placed at intervals in the row of blades, which strips are preferably thicker than the battens, but of similar width, and these strips and battens 7, 8 are recessed at points of their intersection like the blades to interlock at said points, and nails 10 (Fig. 4) driven transversely through the battens and into said strips secure the battens to the strips.

Against the outer lateral sides of battens 8 are secured a row of horizontally spaced, vertical, parallel slats 11. The cross-sectional contour of these slats is preferably, generally triangular, as shown in Fig. 4, or they may be substantially semi-cylindrical, as shown by slat 12 in Fig. 5.

In Fig. 4 each slat is seen to have a wide, planar base side against battens 8 with adjoining, parallel V-grooves 13 formed therein from end to end of the slat to provide open channels for draining moisture and to provide increased evaporating surface.

The nose of each slat, facing outwardly, is of parabolic contour merging into a true circular contour at points about midway of the two outer sides and the opposite edges of the base side are rounded in continuation of said circular curve, the latter being inscribed about a center positioned about midway across the base side, all as shown on Fig. 4.

Where slats 11 are used in connection with blades of substantially the dimensions described, I have found that each of slats 11 may have a

width across the base side of about two inches, which is found to be satisfactory.

The slats 11 are spaced apart a distance to bring the adjacent slats of each pair thereof in the row of slats directly outwardly of alternate blades 6 with the plane of each of said alternate blades substantially bisecting the slat 11 adjacent thereto. Thus the opposite edges of the sides of the slats 11 extend about half way across the spaces between the blade nearest thereto and the blades at opposite sides of such blade. Nails 10' convergently extending from the convergent outer sides of slats 11 and into battens 8 secure the slats 11 to said battens.

Across the outer sides of the slats 11 are battens 14, which are positioned at about the same levels as battens 8. The battens 14 engage the rounded edges of slats 11 that are opposite the sides engaging battens 8, and are secured in place by nails 15 that pass through some of the slats 11 and into batten 8, as indicated in Fig. 4.

The battens 14 are principally for the purpose of spacing a second row of slats 16 outwardly of slats 11. The slats 16 are of the same shape as slats 11, and are similarly grooved at 13' on the base sides, which sides are against battens 14 and face inwardly toward the inside of the tower. Nails 10'' secure slats 16 in place, and said slats are spaced from each other the same distances as slats 11 are spaced from each other. However, slats 16 are offset to directly over the spaces between slats 11, and the spacing is substantially equal to the width of the slats across their base sides; it is obvious that air cannot pass directly through the tower, horizontally, and along lines substantially parallel to the planes of blades 6, without obstruction. As the horizontal width of the battens 14, for the size of slats shown in the drawings, is about one inch, or slightly less, and as the thickness of slats 11, 14 in the direction normal to their base sides is about one inch, it will be seen that horizontally flowing currents of air may, however, readily pass around the slats, with the minimum of resistance, and through the tower.

In some installations, the use of two rows of slats, as described up to this point, and in combination with the row of blades, may be adequate, but I preferably add a third row of slats 17 positioned outwardly of the slats 16, which slats are similar to slats 11, 16 in shape, and are secured to battens 18 which are similar to battens 14. Nails 10''' secure the slats 17 to battens 18 and also nails (not shown) similar to those indicated at 15, may secure the battens 18 in place against slats 16. The slats 17 are positioned directly over the spaces between slats 16 and said slats 17 are grooved on their inner sides at 13'' in the same manner as slats 11, 16 are grooved.

In the tower illustrated in Fig. 1, the width of each side of the tower comprises two panels of blades, slats and battens, as above described, which panels adjoin along a vertical medial line of each wall, and are secured to a vertical post 19 of the tower frame. In Fig. 2 the manner of securing said panels at their adjacent edges is best illustrated, and in Fig. 3 a vertical section further illustrates this construction in which bolts 20 extend through post 19 at vertically spaced points, which bolt passes between vertical strips 9' at the ends of the rows of blades 6 in adjacent panels, which strips are similar to strips 9. Generally U-shaped clamps 21 extend across the outer edges of strips 9' through which clamps the

bolts 20, respectively, extend with a suitable washer and nut on the outwardly projecting end of each bolt securing each clamp tightly against the strips 9' and clamping said strips to the post 19.

Vertical strips 22 outwardly of the adjacent ends of battens 18 of each panel extend over said ends and are secured in said position by any suitable means.

In Figs. 1 and 3 it will be seen that the rows of battens 11, 16 and 17 are successively disposed at slightly higher elevations in direction outwardly from row of blades 6. The lengths of the blades 6 and battens of each row are substantially the same, with the ends of the blades and battens in each row in alignment, and above and below the opposite ends of the blades and battens of each panel is a shelf 23 inclined to correspond to the plane in which said ends are disposed while across the width of each side of the tower and against the outer edge of each shelf 23 is secured a horizontal strip 24 that extends above and below said shelf to overlap the upper and lower adjacent ends of slats 17 of superposed panels.

In Fig. 1 it will be seen that the lowermost panels of the tower also rest on a shelf 23' that is similar to the shelves 23.

These shelves incline in the direction of their widths downwardly from their outer edges, hence any moisture draining from the blades 6 and the slats of the several rows, in each panel, will be directed back into the tower.

The foregoing construction greatly facilitates the rapid construction of a cooling tower, since the panels may be prefabricated, and quickly secured in place.

In Fig. 2 the flow of air across the tower from one side to the other and out is indicated at A, A' by dash lines and arrows. The windward side of the tower, in this instance, is designated W, and the leeward side L.

The lines A' show the path taken by air entering between a pair of adjacent slats 17 while the lines A indicate the path of air striking the outer sides of slats 17.

Wherever, herein, slats are referred to such as slats 11, 16, 17, the modified form of slats as shown in Fig. 5, may be considered as being suitable for use, although the shape of the slats 11, 16, 17 is preferable.

In further explanation of the construction described, in the open-wing louver towers heretofore most generally used, with wind greater than about seven miles per hour, the water travels across the tower due to the wind action, and therefore at the bottom of the tower the cooling surface exposed to the air is considerably less than at the top.

With the shape and arrangement of slats and blades, of this invention, referring to Fig. 2, the rounded noses of the slats and the stream line cross-sectional shape of the blades, offers the minimum of resistance to the air approaching the windward side of the tower. The shape of the slats on the leeward side, and their arrangement, result in greater retardation of the air current for a given velocity than is caused by the windward elements. Thus it will be seen that the shape and arrangement of the slats and blades as hereinbefore described, irrespective of the direction in which the wind is blowing, results in a great retardation of air velocity encountering the dropping water in the tower, when there is a high velocity wind. And it is further apparent that the resistance pressure on the leeward slats of the tower is very slight compared with re-

sistance pressure encountered by the approaching wind at the windward slats, because the resistance increases rapidly as the approaching wind velocity increases. If the flat inner face construction of the leeward slats were used against the approaching wind, the resistance offered thereby to the approaching wind at the windward side would be objectionably great.

With the tower of my construction, as the wind passes over and around the tower, a low pressure area is developed at the top of said tower, and at the leeward side, which low pressure acts as a suction ventilating force in the tower. This suction force thus developed, tends to cause more air to pass through the tower, than otherwise would be the case.

With the construction as shown and described herein, it is estimated, as the result of tests, that with about a five mile per hour wind, the air flow across the inside of the tower is about one and one half miles per hour, while with about a ten mile per hour wind, the air flow through the tower is about three miles per hour, and with a twenty mile per hour wind, the air flow across the tower will be about six miles per hour.

In certain districts, towers are subject to prevailing winds of from fifteen to twenty miles per hour, and in such districts, with towers as heretofore described the wind velocity would be decreased, as it passes through the tower to the desired velocity for best efficiency in eliminating drift losses and for cooling.

Splash from the falling water encountering the splash decks thereon, or the like, will be intercepted by the leeward blades and slats, and will be drained onto the inclined drainage strips or shelves 23, 23', and from thence back into this tower. Also the grooved faces of the slats and the sides of the blades offer large and effective cooling surfaces. With proper water distribution at the top of the tower the application of the vertical slats and blades, as distinguished from the conventional enclosed louvers, adds about 35% to the fixed cooling surface of the tower.

In summary, it will be seen that this invention eliminates splash and drift losses, due to mechanical arresting of the drops and the reduced velocity of the wind across the interior of the tower, and supplies an additional cooling area. The mere reduction of air velocity is not adequate in itself to fully accomplish any of the desired results, thence the particular manner of controlling the velocity plus the increase in evaporating surfaces, as herein disclosed, are very important.

Having described my invention, I claim:

1. A cooling tower having a pair of opposed side walls, each of said side walls comprising a row of spaced, elongated members in side by side relation, providing a passageway between adjacent members for passage of air to within the tower at one of said side walls and from within the tower outwardly at the other of said side walls, substantially the entire outwardly facing sides of said members being generally convex in cross-sectional contour to reduce resistance to flow of air to within said tower.

2. A cooling tower having a pair of opposed side walls, each of said side walls comprising a row of spaced, elongated members in side by side relation providing a passageway between adjacent members for passage of air to within the tower at one of said side walls and from within the tower outwardly at the other of said side walls, substantially the entire outwardly facing sides of

said members being generally convex in cross-sectional contour and the inwardly facing sides of said members being substantially planar, thereby producing a greater resistance to flow of air from within the tower outwardly than from outside the tower inwardly at said walls.

3. A cooling tower having a pair of opposed side walls, each of said side walls comprising a row of spaced, vertically extending elongated members in side by side relation providing a passageway between adjacent members for passage of air to within the tower at one of said side walls and from within the tower outwardly of the other of said side walls, substantially the entire outwardly facing sides of said members being generally convex in cross-sectional contour to reduce resistance to flow of air to within said tower and the inwardly facing sides of said members being formed with convergent sided adjoining grooves extending longitudinally of said members to provide an increased evaporating surface for moisture collected thereon and also to provide drainage channels for said moisture.

4. A cooling tower having a pair of opposed side walls, each of said side walls comprising a plurality of pairs of elongated, vertically extending slats in side by side relation, said slats being generally triangular in cross-sectional contour and arranged with one of the flattened sides of the slats of said row in planar relation facing inwardly toward the insideside of the tower, the remaining outwardly facing two sides of the slats being equal in width and free from concavity in cross-sectional contour, the corner of each slat facing outwardly of the inside of the tower being convexly rounded and being a continuation of said two sides whereby air currents at the windward side of the tower provided with said slats will pass over said two sides and past the adjacent slats of each pair free from objectionable resistance and free from the formation of objectionable eddies in said air currents.

EDWARD W. SIMONS.
